SEALED PACKAGE

Banks D. Brown, Connellsville, Pa., assignor to
 Capstan Glass Company, Connellsville, Pa., a
 corporation of Delaware

Application August 1, 1933, Serial No. 683,133

5 Claims. (Cl. 215—46)

The present invention pertains to the sealing art, and more particularly to a sealed package and the parts thereof.

The number and quantity of food products and the like packed in glass containers increases yearly. The quality and condition of the products when they reach the consumer depend, in a large measure, upon the security of the seal. Spoilage of as much as one per cent of a packer's product is a serious objection and, for this reason, packers demand greater security in seals. The ultimate consumers, mostly housewives, demand a package which can be opened readily. Seals formed by compressing a gasket between the skirt of a cap and the outer side wall of a container, usually by reforming the skirt of the cap, provide a very secure seal. These seals are commonly called "side seals", and will seldom leak because of the tightness thereof and because there is little likelihood of irregularities in the side wall of the container where the seal is made. The tighter the seal is made by reforming the skirt, the harder the package is to open, occasioning complaints on the part of the consumer. The consumer particularly objects to the side seal because a cap opener or other device is necessary for opening the package. Frequently, the housewife does not have an opener and if she does, she must know how to use it for opening the package. Various attempts have been made to overcome these difficulties, but none have succeeded. Attempts to facilitate removal have usually resulted in impairing the security of the seal and attempts to improve the seal have usually increased the difficulty of removing the cap.

The present invention aims to overcome these difficulties by facilitating and simplifying the removal of the caps, regardless of the tightness of the seal, thus satisfying both the consumer and the packer. The invention also contemplates an improved tumbler which facilitates removal of a closure cap without impairing its subsequent use as a drinking tumbler.

An object of the invention is to facilitate removal of the caps from glass containers.

Another object of the invention is to facilitate the removal of closure caps, particularly side seal closures, without impairing the security of the seal.

Another object of the invention is to provide an improved container adapted to facilitate the removal of the caps therefrom without marring its appearance or impairing its utility for reuse.

Another object of the invention is to provide a cap removing attachment for glass containers

particularly tumblers, without marring the appearance thereof.

Another object of the invention is to provide an improved attachment for a container to remove side seal closures therefrom.

Another object is to provide a sealed package with an attachment for removing closures without the use of tools or devices other than the attachment on the container.

Other and further objects of the invention will be obvious upon an understanding of the illustrated embodiment about to be described or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein:

Fig. 1 is a perspective view of a container, here shown as a tumbler, embodying the invention;

Fig. 2 is a fragmentary perspective view illustrating a modified form of protuberance;

Fig. 3 is a fragmentary sectional view illustrating one form of closure cap applied to the container;

Fig. 4 is a fragmentary sectional view illustrating another form of closure cap applied to a container;

Fig. 5 is a fragmentary sectional view illustrating the completed sealed package with the opening attachment applied thereto;

Fig. 6 is a perspective view of the opening attachment apart from the package;

Fig. 7 is a perspective view of another form of opening attachment; and

Fig. 8 is a modified construction illustrating a protuberance for attaching a bail thereto.

Referring again to the drawing illustrating the preferred embodiment of the invention, there is shown a container 1, a closure cap 2 sealed to the container, and an attachment 4 for removing the closure cap from the container. Details of these elements will now be described in the order named.

The container 1 is here illustrated as a glass tumbler, although it will be understood that the invention is applicable to other types of containers. The tumbler may be of the usual shape, but is preferably provided with a bevelled portion 5 adjacent the upper part of the rim, to facilitate the removal of the closure, and a substantially cylindrical sealing surface 6 directly below the bevelled surface, to which the cap may be sealed.

A protuberance 7 which may, for convenience, be provided in a number of forms, is shown herein in having a flat upper surface 8 spaced directly below the sealing surface 6, having an outer surface 5 tapering inwardly and downwardly, as shown at 9, until it merges into the contour of the tumbler. The sides of the protuberance may be rounded or substantially perpendicular to the side wall of the container, as shown at 10. The advantage of having the end corners, or at least one of them substantially perpendicular to the side wall of the container is to minimize the tendency for the knife or other prying tool to be forced off when the corner is used as a fulcrum 15 for prying the cap off. The tapered outer wall of the protuberance strengthens the protuberance and adds to the appearance of the container.

Products packed in tumblers ordinarily are quite popular because the housewife, in many instances, uses the tumbler as a drinking glass or for other purposes. A ledge extending completely around the tumbler impairs its use as a drinking glass but a small protuberance, as illustrated, has been found not to be objectionable. The taper 9, in addition to strengthening the construction, also permits of the molding of a legend such as a number, here shown as 53, to indicate the particular packer's product. Such a legend or trade-mark is conspicuous and can be made with the usual block molds, commonly used for tumblers. The upper surface 8 of the protuberance may be cross-hatched or roughened, as shown at 11, (Fig. 2) to facilitate the application of a pry-off tool for removing the closure cap. This surface may also be recessed, as shown at 12, to facilitate the attachment of an opener, as described hereinafter.

Various types of closure caps may be utilized in the present invention. Two types are shown herein for illustrative purposes, in Figs. 3 and 4. In Fig. 3, the closure cap 2 comprises a cover portion 14 and a depending skirt 15 having a bead 16 adapted to receive and retain a gasket 17. The bead 16 of the closure cap preferably is reformed by suitable chucks or spinning rollers adapted to compress the gasket tightly against the sealing surface 6 below the bevelled surface 5 and slightly above the upper surface 8 of the protuberance 7.

In Fig. 4, a closure 2 is shown with a cover portion 14a and a depending skirt 15a, with the lower edge turned inwardly to support the gasket 17a. The central portion of the skirt may be grooved inwardly, as shown at 18, to compress the gasket. This type of closure cap is adapted to be pressed on the container, the groove 18 of the skirt being sufficiently small to compress the gasket against the container to form a seal. The bottom of the skirt is spaced slightly from the upper surface 8 of the protuberance.

If the packages are sold as illustrated in Figs. 3 and 4, without the attachment 4 illustrated in Fig. 5, the housewife merely has to insert a knife or a coin between the upper surface 8 of the protuberance 7 at the bottom of the cap to pry the cap off the container. It is contemplated herein that a substantial proportion of the packages will be sold without the cap openers 4, since the latter increase, to a small extent, the cost 65 of the package and many packers may desire to forego the advantages of the attached opener to economize in the cost of the package.

The preferred form of cap opener is illustrated on a package in Fig. 5, and apart from the package in Fig. 6. The cap opener preferably com-

prises a handle part 19, the lower end of which may be provided with portions bent into a plane substantially perpendicular to the plane of the handle at 20 to facilitate oscillating the handle along the wall of the container for prying off the closure cap. Preferably, the portions 20 are so shaped that it is difficult to pull the opener away from the tumbler, but easy to move it sidewise. In this manner, correct opening of the package is insured without instructions. If desired, suitable arrows (Fig. 1) may be formed in the side wall of the container to indicate the direction in which the opener should be moved. The other end of the opener is preferably offset at 21 to fulcrum upon the upper surface 8 of the protuberance of the tumbler and to engage the lower edge of the closure cap. The extreme end of the opener is bent downwardly at 22 to nest in the recess 12 of the protuberance.

In Fig. 7, another form of opener is shown having a substantially crescent shaped depending portion 22 adjacent to the fulcrum part 21, adapted to fit into the recess 12 of the protuberance. The ends of the portion 22 project upwardly at 23 to provide prongs for engaging the gasket 17 of the closure cap. If desired, the prongs may be sharpened slightly so that they are adapted to pierce the gasket to break the vacuum in the package.

In assembling and sealing the package, the tumbler is first filled with the product to be sealed and the attachment 4 may be secured to the protuberance 7, either before or after the product is placed in the container. Thereafter, the tumbler, with the opener on it, is placed in a sealing machine, which may be a vacuum sealing machine adapted to remove air from the package and to seal the tumbler to the container by reforming the skirt of the cap, as shown in Fig. 3, or by pressing the cap on the container, as shown in Fig. 4. In either case, the bottom of the skirt of the cap is preferably sufficiently near the upper surface of the protuberance to prevent loss of the opener during shipment and, if desired, to prevent removal of the opener without removal of the cap.

In opening the package, the handle of the opener 19 is oscillated in either direction along the surface of the container by pressure on the flat portions 20. The portions 20 are preferably pressed together, as shown in Fig. 7, to make it difficult for one to pull the lower end of the opener outwardly, this not being the correct way to operate it. The portion 21, by reason of the oscillation, is forced upwardly against the cap to pry it off the container. The sharp projections 23 (Fig. 7) formed at the end of the opener for piercing the gasket, break the vacuum and decrease the amount of effort required to remove the cap. The bevelled portion 5 of the container further facilitates removal of the cap, since it minimizes the stretching of the cap necessary to clear the rim thereof. In this way, the cap can be readily removed without deforming it materially and can be pressed on the container thereafter to provide substantially a hermetic seal during the consumption of the contents.

In Fig. 8, a protuberance is shown in which a recess 24 is provided at the lower part thereof for the reception of a bail 25. It will be understood that where it is desired to use the bail, at least two protuberances will be required at diametric points of the tumbler. The bail may be used with or without the opener.

It will be seen that the present invention provides a tumbler having substantially all of the re-

use values of the ordinary tumbler and also having an attachment which does not mar the appearance of the tumbler and which facilitates the removal of the cap therefrom. The cap opener, to minimize cost, is preferably formed of suitable sheet metal and is adapted to be attached to the protuberance in a simple and effective manner. The closure cap may be sealed on the container without material interference with either the protuberance or the cap opener and, when sealed on the container, automatically prevents the cap opener from being removed from the recess 12 by accident and retains the cap opener in proper position for removal of the cap. The consumer merely oscillates the opener, whereby the vacuum is broken and the cap is pried off. The seals may be formed as tight as desired, without complicating the removal of the cap. The tumbler may be used with the ordinary types of closure caps, with or without the opener attachment, thereby increasing its sales possibilities. The cost of the tumbler is not increased since it may be made on block molds, as tumblers are ordinarily made. In addition, the packer's trade-mark may be conspicuously placed on the protuberance without extra cost.

As various changes may be made in the form, construction and arrangement of parts herein without departing from the spirit and scope of the invention and without sacrificing its advantages, it is to be understood that all matter herein is to be interpreted as illustrative and not in a limiting sense.

Having thus described my invention, I claim:

35 1. As an article of manufacture, an opener comprising a handle part made of flat material, portions at one end of the handle part being bent at substantially right angles to the plane of the handle, the other end of the handle part being 40 offset to form a fulcrum part, a portion bent downwardly from the plane of the fulcrum part and in the direction of the handle, and upwardly extending prong-shaped portions at the ends of the downwardly depending part for engaging and 45 piercing a gasket within a closure cap sealed to a glass container, said prong-shaped portions being adapted to vent the package and thereafter remove the closure from the container.

2. A sealed package comprising in combination, a tumbler having a sealing zone beneath the rim thereof and an integral protuberance on the side thereof, said protuberance provided with a substantially flat upper surface being slightly below the sealing zone and an arcuate recess 55 tending downwardly, at said upper surface to provide a concave upward fulcrum portion for a cap removing tool, a closure cap having a gasket in the skirt thereof, said skirt being reformed to force said gasket against the sealing zone on the side wall of the tumbler to form a side seal thereon, the bottom of said skirt being spaced slightly from the upper surface of said protuberance, and

a cap removing member having an arcuate portion seated in said recess in said protuberance for prying the cap from the tumbler.

3. A sealed package comprising in combination, a glass container having a bevelled rim to facilitate removal of a closure cap, a sealing zone beneath said rim and an integral protuberance, the upper surface of the protuberance being below said sealing zone of the container and having a bearing provided by a recess extending downwardly from the upper surface adapted to act as a fulcrum for a cap removing member, a closure cap forming a hermetic seal on the side wall of the container, and a cap removing member having a portion seated in said recess on said bottom adapted to engage and remove the closure cap.

4. A sealed package comprising in combination, a glass container having a sealing zone at the upper end thereof for receiving the skirt of a closure cap and having an integral radially outwardly extending circumferentially short projection spaced a slight distance below said sealing zone, said projection having a substantially horizontal upper surface with end corners substantially perpendicular to the side wall of the container to serve as a fulcrum for a pry-off tool and to minimize the tendency of the prying tool to be forced out of its operating position when a closure cap is being pried from the container, and an outer side surface tapered downwardly and inwardly to merge into the side wall of said container, the outer side surface being of substantial length and longer than the distance the upper surface projects outwardly, and a closure cap sealed on said sealing zone having the lower edge of the skirt thereof adjacent to said projection.

5. A sealed package comprising in combination, a glass container having a side wall sealing zone adjacent the upper end thereof adapted to fit 40 within the skirt of a closure cap and having an integral radially outwardly extending circumferential projection spaced a slight distance below said sealing zone, said projection having a substantially horizontal upper surface with an end 45 corner substantially perpendicular to the side wall of the container to serve as a fulcrum for a pry-off tool and to minimize the tendency of the prying tool to be forced out of its operating position when a closure cap is being pried from the container, and an outer side surface tapered downwardly and inwardly to merge into the side wall of said container, the outer side surface being of substantial length and longer than the distance the upper surface projects outwardly, and 55 a closure cap having a sealing gasket in the skirt thereof, said skirt being reformed to compress said gasket between said sealing zone and the skirt of the cap to form a seal with the lower 60 edge of the skirt of the cap adjacent to the upper surface of said projection in sealed position.

BANKS D. BROWN.
